SANITARY INSERT FOR BASINS

Original Filed April 18, 1935

UNITED STATES PATENT OFFICE

2,048,968

SANITARY INSERT FOR BASINS

George V. Riley, Washington, D. C.

Original application April 18, 1935, Serial No. 17,096. Divided and this application September 7, 1935, Serial No. 39,657

1 Claim. (Cl. 4—166)

My invention relates broadly to basins and more particularly to a sanitary insert for basins.

This application is a division of my application Serial No. 17,096, filed April 18, 1935, for 5 Automatic sanitary insert basin.

This invention is directed to a construction of sanitary insert, especially constructed for use in my automatic insert basin set forth more fully in my aforesaid application Serial No. 17,096.

10 One of the objects of my invention is to provide a construction of sanitary insert for basins wherein the insert is formed from a cellulose product which is normally folded flat and which is readily unfoldable for lining the basin.

15 Another object of my invention is to provide a construction of cellulose insert for basins having walls which are normally folded in surface contact and end portions substantially in the nature of web members which may be folded 20 inwardly to allow manifolding of the insert in a magazine carrier and being readily unfoldable for lining the basin.

25 Still another object of my invention is to provide a construction of sanitary insert which is capable of being folded and stacked in manifolded relation in a magazine carrier and successively supplied to a basin.

30 A further object of my invention is to provide a construction of fluid-tight sanitary insert for basins which is substantially trough-like in contour and capable of being folded into a relatively narrow rectangular package.

35 A still further object of my invention is to provide a construction of foldable cellulose insert for basins where the insert may be folded into a compact flat substantially rectangular package in manifolded relation to similar inserts.

40 Other and further objects of my invention reside in the construction of a foldable insert for basins as set forth more fully in the specification hereinafter following, in which:

45 Figure 1 is a perspective view of the sanitary insert of my invention; Fig. 2 is a side elevation partially in longitudinal section showing one of the sanitary liners of my invention; Fig. 3 is a top plan view of one of the sanitary liners; Fig. 4 is a side elevation of the sanitary liner shown in Fig. 3 showing the liner as it appears when 50 folded in a flat substantially rectangular package capable of manifold relation with similar sanitary inserts; Fig. 5 is a top edge view showing the sanitary liner as it appears when folded; Fig. 6 is a transverse view through the sanitary liner taken on line 6—6 of Fig. 4, the liner be-

ing unfolded; Fig. 7 is a fragmentary sectional view illustrating the arrangement of the sanitary liners of my invention in manifolded relation mounted with respect to the mechanism for selectively delivering sanitary basin liners; 5 Fig. 8 is a view similar to Fig. 7 showing the next successive step in the delivery of sanitary basin liners through the selective feed mechanism; Fig. 9 is a view similar to Figs. 7 and 8 but showing the sanitary liner as it appears in 10 the basin in use for retaining liquid; Fig. 10 shows one step in the process of ejection of the sanitary liner from the basin; and Fig. 11 shows the manner in which the sanitary liner is ejected 15 from the basin into the drain housing beneath.

My invention is directed broadly to a construction of cellulose sanitary liners for basins. The sanitary liner which I have illustrated has been developed particularly in connection with wash 20 basins, but I desire that it be understood that the sanitary insert of my invention may be employed for basins used to hold liquids of any description for medical treatments in doctors' and dentists' offices, in chemical research laboratories, and in other instances where quantities of liquid must be maintained in a vessel. My invention is intended primarily for use in the automatic insert basin set forth more fully in my parent application Serial No. 17,096, filed 30 April 18, 1935, supra, which provides means for successively supplying to a basin a sanitary liner of cellulose material which is normally folded and arranged in manifold relation with similar liners in a magazine carrier. The construction 35 of the liner is such that the flat walls thereof may be readily unfolded to form a liquid retaining receptacle in a basin having perforate walls. The construction of the basin is such that it will not normally retain fluid. However, when a sanitary liner is inserted in the basin and opened to conform with the internal shape of the basin, fluid can be retained in the liner forming the receptacle. The present application shows means for ejecting the liner after 45 use. For this purpose a drain housing is provided beneath the basin and connected with the drain from the basin. An ejecting mechanism is employed to effect the discharge of the used liners to a position within the drain housing. At 50 periodic intervals, the used liners are removed from the drain housing.

Where it is desired to employ the sanitary liners for wash basins in public places, such as hotels, comfort stations, railroad trains, etc., I 55

may arrange a coin control mechanism whereby, upon the insertion of a coin and the actuation of a lever, a liner may be moved into position within the basin. The coin control mechanism is not an essential part of the apparatus as I may actuate the sanitary liner feed mechanism by successive operations of the hand lever without the employment of a coin control mechanism.

10 The sanitary liner which I have illustrated for purposes of explaining my invention may be formed from a cellulose product which is substantially liquid-proof to insure the retaining of the liquid within the basin. I have illustrated 15 the cellulose insert in Figs. 1-6 from which it will be seen that there are two flat wall portions 3a and 3b which may be folded in flat surface contact as shown in Fig. 5. The side walls of the insert may be folded as shown at 3c and 3d 20 to insure a flat structure capable of manifolded assembly while readily permitting the unfolding of the end portions 3c and 3d to the position illustrated in Figs. 2, 3 and 6. Various forms of cellulose materials may be used and a 25 selection of the exact material is not important. I have found paper which is waxed or otherwise treated to be practical as a manifolded insert.

I make provision for folding the side walls 3a 30 and 3b through the agency of the web-like end portions 3c and 3d, which when folded inwardly allow the sanitary insert to be collapsed to a substantially rectangular package. This facilitates the manifolding of the sanitary inserts in the delivery mechanism which I have shown 35 herein for the purpose of explaining the nature of the problem which must be made in the construction of the sanitary insert of my invention.

The sanitary liners 3 are stored in manifolded 40 relation as indicated at 13 in a magazine carrier 54 located directly beneath the front of the top section 50 of the fixture constituting the basin as illustrated. The magazine carrier 54 supports the liners in manifolded relation as indicated at 13 in a position in which the liners 45 3 may be successively fed to the basin by a vertically upward movement. Fig. 8 illustrates one of the liners 3 being fed in a vertical direction intermediate the end plate 55 and the edge 56 of the top section 50 and through the slot 57 formed in the upper portion of the magazine carrier 54. The sanitary liners 3 are continuously urged in the direction of plate 55 by means 50 of springs 21 acting between the inside face of the magazine carrier 54 and the follower plate 55 59. The feed mechanism for the sanitary liners 3 includes the liner pickup fingers 14 carried by a laterally extending bar member 17. The pickup bar member 17 is mounted to move with a slight amount of lost motion in the ends of 60 the pickup bar arms 16 so that the liner pickup fingers may follow each sanitary liner successively for insuring the delivery of each sanitary liner in a vertical path. The pickup bar arms 16 are carried by a pivoted bar 19 which is journaled in bracket members 60 mounted on the rear 65 surface of the magazine carrier 54. An operating lever 20 is connected with the pivoted bar 19 and to the pickup arms 16 and has an end grip 61 thereon which may project beyond the front of the top section 50 in a convenient po-

sition and manually gripped for angularly shifting the liner pickup fingers 14 and effecting the ejection of each successive sanitary liner 3. The pickup bar 17 is adapted to slide vertically within limits defined by the pickup bar guide slot 26 5 formed in the vertically extending portions of the end closures of the basin indicated at 49 in the cross sectional views.

The lever 20 is normally maintained in an extreme upper position illustrated in Figs. 7, 9 and 10 by means of a suitable coil spring. With each successive actuation of lever 20 the coil spring returns lever 20 to its extreme uppermost position ready for its successive operation.

In order to replenish the supply of sanitary 15 liners in the magazine carrier I provide a refill door 15 hingedly mounted at 31 to allow sanitary liners in manifold relation to be inserted into the compartment as the liners are used from time to time. A suitable lock 62 is provided for preventing unauthorized access to the magazine carrier.

In order to open the refill door 15 the lock 62 is unlocked, the sanitary liners in manifold relation inserted in the compartment and the successive feeding of the sanitary liners thus continued.

The sanitary liner 3 is substantially trough-like in contour and has the major longitudinally extending axis thereof exceeding in dimension 30 the lateral axis normal thereto. The V-shaped construction of the sanitary insert which conforms with the sides of the recessed portion of the basin in which it is inserted is an important factor in determining the strength of the sanitary insert. It is important that the insert have considerable strength in order that the insert may be practically employed in the delivery mechanism which I have explained. When the sanitary insert is unfolded, the walls conform 40 with the sides of the basin for which it provides a sanitary liner.

While I have described a preferred embodiment of my invention I desire that it be understood that modifications may be made, and I intend no limitations upon my invention other than may be imposed by the scope of the appended claim.

What I claim as new and desire to secure by Letters Patent of the United States is as follows:

A sanitary insert for basins comprising an element of sheet-like material foldable in a substantially rectangular package adapted to be ejected from a magazine carrier, said element comprising a pair of side wall portions and a pair of triangular shaped end wall portions of web-like construction interconnecting opposite ends of the side wall portions, said web-like end portions being normally folded inwardly to permit said liner to be maintained in a flat package and being unfoldable to allow said side walls to be moved to a position angularly displaced with respect to each other for forming a substantially fluidtight container, said container being collapsible along substantially the center of the side walls thereof for allowing ejection of the container after use thereof.
